United States Patent

Des. 236,073
Patented July 29, 1975

236,073

BOTTLE SCRAPER

William P. Monagle, 507 Pueblo St.,
Boise, Idaho 83702

Filed Feb. 28, 1974, Ser. No. 446,873

Term of patent 14 years

Int. Cl. D7—05

U.S. Cl. D7—184

fig. 2

FIG. 1 is a left front perspective view of the bottle scraper embodying my new design.

FIG. 2 is a right rear perspective view of the bottle scraper of FIG. 1 as viewed from the bottom.

I claim:

The ornamental design for a bottle scraper, substantially as shown.
